(57) CLAIM

I claim the ornamental design for the shoe sole, as shown and described.

DESCRIPTION

FIG. 1 is a bottom, front, right side perspective view of a shoe sole according to the present invention;

FIG. 2 is a bottom plan view thereof;

FIG. 3 is a left side elevational view thereof;

FIG. 4 is a right side elevational view thereof;

FIG. 5 is a rear elevational view thereof; and,

FIG. 6 is a front elevational view thereof. The broken lines in the drawings showing the shoe mid-sole and upper, a brand logo tag, tread patterns, and other portions of the shoe sole illustrate the portions of the design that form no part of the claim.
